[57] CLAIM

The ornamental design for a toy soccer game assembly, as shown.

DESCRIPTION

FIG. 1 is a perspective view of the toy soccer game assembly of the instant invention;

FIG. 2 is a front elevational view of the character figure thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view of the goal portion of the game assembly;

FIG. 9 is a rear elevational view thereof;

FIG. 10 is a right side elevational view thereof;

FIG. 11 is a left side elevational view thereof;

FIG. 12 is a top plan view thereof; and,

FIG. 13 is a bottom plan view thereof.
